UNITED STATES PATENT OFFICE.

FLOYD E. TOWNSEND, OF BERKELEY, CALIFORNIA, ASSIGNOR OF ONE-HALF TO E. G. PALMER, OF SAN FRANCISCO, CALIFORNIA.

CAR UNLOADER.

Application filed November 29, 1920. Serial No. 426,913.

To all whom it may concern:

Be it known that I, FLOYD E. TOWNSEND, citizen of the United States, residing at Berkeley, in the county of Alameda, State of California, have invented a new and useful Car Unloader, of which the following is a specification in such full and clear terms as will enable those skilled in the art to construct and use the same.

10 This invention relates to a car unloader and its object is to produce a machine which is capable of swinging an elevator leg transversely from side to side of the car and also being capable of moving the elevator leg 15 longitudinally of the car a sufficient amount to unload a good portion of the car without moving the car or the elevator supporting apparatus.

20 A further object of the invention is to provide an unloading apparatus which will be as low as possible in order to enable it to be admitted to docks and railway stations where low doors must often be passed through.

25 Another object of the invention is to reduce the total height of the complete apparatus in operation as much as is consistent with the elevation of the materials handled, to a discharge chute, to a bin or to a truck 30 body.

Another object of the invention is to provide the apparatus with a control mechanism which will all be located conveniently adjacent the position of the operator, his platform being placed high enough for him to observe the operation of the elevator at all 35 times.

Other objects of the invention will appear as the description proceeds.

40 An embodiment of the invention is shown in the accompanying drawings in which the same reference numeral is applied to the same portion throughout, but I am aware that there may be modifications thereof.

45 Figure 1 is a side elevation of the complete machine.

Fig. 2 is a view in elevation of the complete machine looking from the left Fig. 1.

50 Fig. 3 is a plan view of the complete machine.

Fig. 4 is an enlarged view of the elevator leg swinging mechanism.

Fig. 5 is an enlarged view of the head frame tilting mechanism.

Fig. 6 is a plan view of the portion of the 55 turn table gear.

Fig. 7 is a plan view of the square shaft used for driving the elevator chains.

The apparatus comprises a suitable truck body 1 mounted on four wheels 2 to 5 inclusive in order that the truck may be transported from place to place readily. The truck body carries a pair of cross beams 9 and 10 which support a platform 11 on the outer edge of which is a ring gear 12.

60 The platform 11 supports a plurality of roller bearings 13, which bearings in turn touch a circular track 14 on the under side of the platform 15.

65 Brackets 16 and 17 placed wherever needed 70 are secured to the under side of the platform 15 and serve to hold the platform from tipping over, in case an undue strain is placed thereon.

75 The platform 15 has a king pin 18 which passes through the platform 11 and serves as an axis about which the platform 15 can turn. At two front corners of the platform 15 there are upwardly extending brackets 19 and 20 which pivotally support two double 80 posts 21 and 22. These posts have suitable bearings at their upper ends for a heavy shaft 23 and they are held in an upright position by means of two braces 24, 25, said braces being connected to the outer ends of 85 the posts 21 and 22 and to brackets 26 and 27 projecting upwardly from the back end of the platform 15.

86 The shaft 23 supports two heavy arms 29, 30, and said arms have two shafts 31, 32 at 90 their ends. The two shafts 31 and 32 and the arms 29 and 30 connect therewith forming a tilting frame for the support of the elevator. This frame is tilted by a screw 33 which passes through a pivotally mounted 95 nut 34 on the arm 30. This screw is turned by the operation of a hand wheel 35 on a shaft 36, said shaft extending through a bracket 37 having two bearing arms 38 and 39 and between which arms the shaft has a 100 worm 40. The worm 40 engages a worm wheel 41 on the screw shaft 33 and said screw shaft passes through a bracket 42 which allows sufficient movement of the screw shaft with respect to the shaft 36 to permit adjustment of the arms 29, 30 and shafts carried thereby.

105 Mounted above the shafts 31 and 32 are

two arms 43, 44, said arms each having two bearing blocks 45 through which the shafts 31 and 32 pass.

The arms 43 and 44 are connected with suitable cross members 45, 46 and 47 which hold said arms in a fixed position relatively to each other for the support of the elevator leg 48.

The two arms 43, 44 are adjusted longitudinally of their supporting shafts 31 and 32 by means of two screws 49 and 50. These screws are supported by suitable raised bearing plates 51, 52 carried by the arms 29 and 30. The threaded shafts pass through threaded nuts 53 and 54, carried by the arm 44 and said screws are operated by a hand wheel 55 on the end of the screw 50 over the operator's platform 56. The operator's platform 56 is carried by the post 22 and it has two bracing members 57 and 58 to hold it properly in position.

A sprocket gear 59 on the shaft 50 has a chain 60 passing thereover and around a sprocket gear 61 on the shaft 49 so that the frame consisting of the arms 43 and 44 is always moved parallel to the supporting arms 29 and 30.

Mounted in bearings 61 and 62 on the back end of the arms 29, 30 is a square shaft 63, this shaft passes through collar bearings 64, 65 carried by the arms 43, 44 respectively and it passes through the center of a sprocket gear 66 which is held in position against the collar 64 by means of a strap 67 secured to the back end of the arm 43.

Depending from the front end of the two arms 43 and 44 are two suitably braced elevator frames 70, 71 which frames are supported from an axle 72 on which are two sprocket wheels 73, 74 and a drive sprocket 75.

At the lower end of the frame of the elevator leg there is a shaft 76 carrying two sprocket gears 77, 78. Sprocket chains 79, 80 pass around the sprocket wheels on the elevator frame and they have separate buckets 81 for lifting the materials to be elevated.

Two rearwardly projecting guard rods 82 and 83 prevent the elevator flights or buckets from digging into the sides of the car or digging too deeply into the pile of material to be handled and cutting the floor of the car.

About one-third the distance from the top of the elevator leg there are two links 84 and 85 which are pivotally connected to the elevator leg at 86 and pivotally connected to two other links 87 and 88 by means of a shaft 89. The shaft 89 is enlarged at its center which will receive a threaded shaft 90. This shaft 90 is supported by a U-shaped stirrup 91 extending over the shaft 92. The shaft 92 is in turn supported by the arms 43, 44 and its end opposite from

the hand wheel 93 is supported by a bearing 94 on the arm 29, said bearing also affording means through the collars 95 and 96 for preventing the shaft 92 from moving longitudinally as the arms 43 and 44 are moved longitudinally of the shafts 49, 50. A bearing 97 supports the wheel end of the shaft 92 when the arms 43, 44 are moved at a distance therefrom. The shaft 92 has a feather-way to receive a key 99 carried by the small bevel gear 100, which bevel gear is in mesh with a larger bevel gear 101 on the tip end of the shaft 90.

In order to rotate the platform 15 there is a vertical shaft 105 provided with a small pinion 106 at its lower end and with a hand wheel 107 at its upper end, the hand wheel being in reach of the operator who stands upon the platform 56.

A bearing 108 supports the upper end of the shaft 105 and prevents it from dropping down. The apparatus is driven from a suitable motor 110 on the platform 15, said motor having a sprocket chain 111 which passes around the sprocket wheel 112 freely revoluble on the shaft 23.

At the side of the wheel 112 there is a small sprocket wheel 113 which has a sprocket chain 114 extending around the same and around a sprocket wheel 115 on the squared shaft 63.

It will be observed that whatever position the elevator leg supports 43, 44 may be placed, that the sprocket wheel 66 will be carried along with them and will be driven by the squared shaft 63.

Extending over the sprocket wheel 66 is a sprocket chain 116. This chain in turn extends over the sprocket wheel 75 at the outer end of the supporting arms 43, 44 and drives the shaft 72, which shaft supports the elevator frame and its associated chains and buckets.

The operation of the apparatus is as follows: Assuming it to be necessary to move the truck from one place to another place in which the height of the apparatus is too great to permit it to be moved as it appears in Fig. 1, the motor may be moved to one side on the platform 15 and the braces 24, 25 may be disconnected whereupon the supports 21, 22 will be allowed to swing downwardly and rest upon any suitable support on the platform 15. The only requisite being that when the supports are down, that their upper ends shall be far enough off the ground to prevent the right hand ends of the arms 43, 44 from touching the ground, whereupon the truck may be moved through any ordinary doorway.

When the truck has reached the place where its is to be operated, the posts 21 and 22 will be raised and the braces 24, 25 will be applied as shown in Figs. 1 to 3 inclusive. Thereupon the workman mounts the plat-

form 26 and he will raise the elevator leg high enough to pass over the top of the car to be unloaded by the operation of the hand wheel 35. At the same time he can extend 5 or retract the elevator leg as may be necessary by the operation of the hand wheel 93.

As the car is unloaded he will from time to time move the elevator leg lengthwise of the main supporting shaft 23 by the operation 10 of the hand wheel 55, continuing this operation until he has unloaded a space in the car equal to the length of the shafts 49, 50. The car can then be moved and he will either run the arms 43, 44 back to their original 15 position or may move the car a sufficient amount and continue the unloading until they are restored to their initial position, moving them from time to time as he may require.

20 If it is not intended to run the truck 1 squarely up against the car, or if it is desired to drive it alongside the car, the body 15 may be rotated to any desired position by the operation of the hand wheel 107. It will of 25 course be apparent that any suitable chute may be used to receive the material dumped from the buckets 81 as they pass over the top of the elevator leg, said chutes forming no part of the present invention.

30 What I claim is as follows, but various modifications may be made in the construction shown in the drawings and above particularly described form, within the purview of my invention.

35 1. An apparatus of the character described comprising a truck, supporting posts carried thereby, a tilting frame, arms carried by said frame and movable parallel to its axis, means for tilting the frame, means for moving 40 said arms, a swinging elevator leg supported by said arms, an elevator chain carrying buckets passing around said swinging elevator leg, means to adjust the position of the elevator leg and means to operate the 45 elevator buckets independently of the adjusting mechanism.

2. An unloading apparatus comprising a truck, posts thereon, a tilting frame mounted on the posts, means to shift said frame to 50 and hold it in any desired adjustment, a second frame mounted for transverse movement along the first frame, screws for effecting the movement of the second frame, an elevator

leg supported by one end of the second frame, means to operate the elevator in said leg, 55 and means connecting the second frame and elevator leg for swinging the elevator leg forward or back at will.

3. An unloading apparatus comprising a truck, pivotally mounted posts thereon, braces for holding the posts erect, a tilting frame on the top of the posts, a screw for tilting and holding said frame in any desired adjustment, a pair of connected arms forming a second frame mounted for transverse 60 movement along the first frame, screws for effecting said movement, an elevator leg carried by the second frame, means to operate the elevator in said leg, a pair of connected double links for swinging the elevator leg 65 from said second frame, and a screw connected with said links and with the second frame for swinging the elevator leg backward or forward.

4. An unloading apparatus comprising a truck, posts thereon, a tilting frame mounted on the posts, means to tilt said frame and hold it in any desired adjustment, a second frame mounted for transverse movement on the tilting frame and supported thereby, 80 means for moving said frame back and forth on the tilting frame, an elevator leg supported by the second frame, means to drive the conveyor in the elevator leg from the truck platform, swinging links to move the elevator, an elevated operating platform and manual means adjacent the operating platform for the operation of all of the adjustments.

5. An unloading apparatus comprising a truck, a turn table, an elevated operating platform thereon, posts carried by said platform, means adjacent the operating platform for turning the turn table, a tilting frame carried by said posts, a second frame mounted 90 for transverse movement along the tilting frame, means to move the second frame along the tilting frame, an elevator leg carrying a conveyor supported by the second frame, depending links connected with the elevator leg 95 and with the second frame for swinging the elevator leg and means on the truck for driving the conveyor in the elevator leg.

In testimony whereof I have hereunto set my hand this 22nd day of Nov. A. D. 1920.

FLOYD E. TOWNSEND.
